UNITED STATES PATENT OFFICE.

WILLA DANSON, OF SAN LEANDRO, CALIFORNIA.

DESIGN FOR A STATUETTE.

Application filed June 20, 1922. Serial No. 2,747. Term of patent 7 years.

To all whom it may concern:

Be it known that I, WILLA DANSON, a citizen of the United States, residing at San Leandro, in the county of Alameda and State of California, have invented a new, original, and ornamental Design for a Statuette, of which the following is a specification, reference being had to the accompanying drawing, forming part thereof.

The figure is a perspective view of a statuette, showing my new design.

The printed matter on the drawing forms an important feature of the design.

I claim:

The ornamental design for a statuette, as shown and described.

In testimony whereof I affix my signature.

WILLA DANSON.
